M. STEINTHAL

SAMPLE DEVICE

Filed Jan. 4, 1923

UNITED STATES PATENT OFFICE.

MARTIN STEINTHAL, OF NEW YORK, N. Y.

SAMPLE DEVICE.

Application filed January 4, 1923. Serial No. 610,730.

To all whom it may concern:

Be it known that I, MARTIN STEINTHAL, a citizen of the United States, and resident of New York, in the county of New York and State of New York, have invented certain new and useful Improvements in Sample Devices, of which the following is a specification.

My invention relates to improved means for displaying samples of goods in a handy and compact arrangement, and which may be used in conjunction with an attached trade-list, or certain other data used in ordering goods from the samples. The novel arrangement and construction of my device lends itself particularly to displaying samples of materials shaped or cut in the form of strips or strands, such for example, as fabrics, yarns and like flexible materials, and I have therefore preferred to illustrate my improvements herein, in connection with knitting yarns or flosses, though the invention is, of course, not limited to such commodities.

I have illustrated types of my invention in the accompanying drawings, wherein:

Figure 1, is a front view of a folding sample card embodying my improvements, the card being shown as opened and with the bunches of sample pieces spread out laterally from the two opposite edges of the card.

Figure 2, is a rear view of the same with one flap partly closed and with a portion of the back sheet of the card turned or rolled up, showing the interior construction by which the inner ends of the samples are secured in place.

Figure 3, is an enlarged view in section, of a portion of the same, the plane of the section being indicated by line 3-3, in Fig. 1.

Referring to the drawings, the card 1, in the construction herewith shown, is composed of a front sheet or layer 2, of suitable material, and a back sheet 3, glued or secured together by adhesive substance. The respective groups or bunches of the sample pieces or yarns 4 to 14, are mounted along the opposite edges of the card 1, by inserting the inner ends of the pieces between the card-layers 2 and 3, and pasting or otherwise securing them in fast positions, so that they will withstand much handling without being dislodged. Instead of having the sample pieces protrude directly from

the edge, as may be done, I prefer to set them back a slight distance from the edge so as to leave a marginal portion 15, on the front face of the card, and this arrangement provides a better and neater construction than otherwise. To this end, the sample pieces are passed through perforations 16, formed in the front-sheet 2, and the size of which varies in accordance with the thickness or size of each bunch of samples, the perforation being oblong or circular, as the case may be. The narrow and oblong form of the perforation 16, serves to keep the samples spread out, in a somewhat fan-shape, and thereby maintain their positions in the bunch. The inner attached ends of the samples, as indicated in Fig. 2, at 11^a, 12^a and 13^a, are spread out fan-shaped where they are secured to the inner side of the front sheet 2, by means of glue or paste indicated at 17, which paste also serves to secure the two sheets together. In addition to this, I also paste across the said inner ends of the samples, 11^a, etc., a band or strip 18, having its inner face provided with paste or adhesive 19, and this is securely pressed down against the said ends to aid in firmly anchoring them in place.

At each side of the center line 20, of the card is arranged printed matter in the way of a trade-list, prices, sample-numbers and colors and shades thereof, and a series of horizontal lines 21 extending from said central line to the respective edges mark off areas in which the said data is located adjacent to the respective groups of samples. The said data is indicated at 22, 23 and 24. The column 22, for the samples 4, reading "081 Light blue" "6 Tan" etc., and the column for the samples 11, reading "81 Delft blue" "36 White" etc. At 23 is stated the character and price of the goods in sample 11, namely; "4 Ply, Fibre silk and worsted, 45¢, 2 oz." the latter price and weight referring to a skein of the particular yarn. At 24 appears the words "Knitting yarns" meaning the class of goods of all the samples on the card. Below this where there is a dotted line, may be printed the name of the mill or business concern manufacturing or handling the line of goods represented on the card. In each of the spaces between the horizontal lines 21, and the vertical central line 20, is certain printed matter on the order of that just referred to and the same refers to the adjacent group

2

of samples, as indicated in the rows of dotted lines shown in said respective spaces. The card may also contain printed matter giving instructions as to how to order the 5 goods from the particular concern named at the top, as well as other pertinent information in reference to the particular goods and the makers thereof, including trade-marks, so that the card is quite complete in itself 10 as to all necessary information in connection with the samples displayed by the card.

The number of pieces in the sample bunches vary, so that while one bunch contains say two or three, another may have 15 twenty-four or more pieces of yarn, floss or other material which is to be displayed. As the pieces are compressed where they pass through the perforation in the card, they automatically spread out in tassel form 20 at their free ends, so that they may be easily picked out one piece from the other in examining them to make a selection of the desired samples. It will be noted that at no place in any strand or strip of the 25 sample material, is there a knot or a doubled part, so that there is no unnecessary thickness at any place of the samples, and this is an important advantage in portable sample devices of this character, and 30 particularly when the card as herewith shown, is a folded one, being folded on the center line 20. In this folded form of the card, the samples may be turned inwardly so as to be covered and protected by the 35 two wings or panels of the structure, when the card is not in use or is carried in the pocket. The card may be made in any desired size, and the shape of the same may be any other than the rectangular one here- 40 with shown. The disposition of the various sample groups may be varied from the arrangement here shown, and each edge may have samples along the same, or only one edge be so provided. Instead of the 45 pieces being secured near the edge of the card, they may be located anywhere on the surface of the same to suit a particular user of the article. In the use of this particular construction and arrangement of sample 50 card, I find that the article is superior to an arrangement in which the sample pieces protrude from between the adjacent edges of the sheets of material composing the card, and that it presents a much neater 55 appearance and at the same time holds the pieces of goods together in proper place.

In making my improved sample displaying device herein shown, I use two sheets or layers of material, 2 being the front 60 sheet and 3, the back one, said sheets being pasted or glued together by adhesive 17, to make a substantial card 1. The back sheet also aids in firmly securing the inner ends of the sample pieces in place and reinforces the adhesive strip in this function. 65

As the pasted short ends of the strands extend inwardly from the perforations and the outer edge, there remains a clear unobstructed marginal part between said perforations and edges, of both sheets, for contact and adhering surfaces, and this makes a tight closure at the edge of the card, the joint being completely sealed without possibility of showing any of the strands at such point. This neat finish of the completed card, together with its folding feature which permits of the samples being turned inwardly between the folded wings and thereby protected, as shown in Fig. 7, 75 gives the article desirable advantages in this class of goods, and also makes it more durable. This arrangement of the short pasted ends of the strands also gives a secure anchorage to the same, as such ends are entirely surrounded with the pasted down 80 faces of the contacting layers of the card material between which the ends lie.

As shown in the drawings, the bunches or groups of samples may be made up of one or more pieces, but if preferred each 90 place may be occupied by a single sample piece or strand instead of several as some sample cards are equipped in this way.

Having thus described my invention, what I claim and desire to secure by Letters 95 Patent is;

1. A device for displaying samples, the same comprising means having at designated spaced-apart places thereon groups of samples with their inner ends embedded 100 and concealed therein.
2. In a device for displaying samples, means provided with an opening near one edge, and samples inserted in said opening and protruding therefrom with a margin 105 between said opening and edge.
3. A sample card formed of layers or sheets and having groups of samples mounted thereon at suitably spaced apart intervals, the inner ends of said samples being 110 inserted and secured between layers of said card to conceal and retain the same.
4. A sample card composed of juxtaposed layers of material having a series of perforations through which the ends of samples 115 may be inserted and placed between said layers, and groups of samples inserted through said respective perforations with their inner ends placed between said layers and held therebetween.
5. A sample card having two of its opposite edges provided with groups of samples mounted thereon in spaced apart relation with their free ends projecting from said respective edges, spaces marked off on said card adjacent each of said sample-groups and each space having indicated therein certain data pertaining to its adjacent group of samples.
6. A sample displaying device composed 130

of layers or sheets of suitable material secured together, one of said layers being provided with a series of perforations near one of its edges, one or more sample pieces passing through each of the respective perforations with their inner ends secured between said layers and their outer ends projecting free for inspection.

7. A device for displaying sample pieces

of material, the same comprising a folder 10 having at designated marginal places sample pieces projecting therefrom with free ends, said pieces being arranged to be turned within the folder to house the same.

Signed at New York in the county of 15 New York and State of New York this 29th day of Dec., 1922 A. D.

MARTIN STEINTHAL.
